Vastar 19.6 Inch Drain Snake Hair Drain Clog Remover Cleaning Tool, available in Amazon.com, date first available Apr. 1, 2016 [online], [site visited Sep. 20, 2024], Available from the internet URL: https://www.amazon.com/dp/B01DP871F8/ref=sspa_dk_detail_6 (Year: 2016).*

Primary Examiner — Jennifer Rivard*Assistant Examiner* — Jenny lou M Binas(57) **CLAIM**

The ornamental design for a drain clog remover, as shown and described.

DESCRIPTION

FIG. 1 is a front, top perspective view of a drain clog remover, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is an enlarged bottom plan view thereof;

FIG. 9 is an enlarged view of detail "9" identified in FIG. 1; and,

FIG. 10 is an enlarged view of detail "10" identified in FIG. 2.

The dashed broken lines in the figures illustrate portions of the drain clog remover that form no part of the claimed design. The dash dot dash broken lines in FIGS. 1, 2, 9 and 10 are for the purpose of illustrating the enlarged view indicators and form no part of the claimed design.

1 Claim, 10 Drawing Sheets(56)
